ORGAN CONSOLE

Winsor D. White, Jr., Blowing Rock, N.C., assignor to D. H. Baldwin Company, Cincinnati, Ohio, a corporation of Ohio

Filed July 21, 1965, Ser. No. 86,238

Term of patent 14 years

(Cl. D56—2)

Fig. 1

FIG. 1 is a front, top and right side perspective view of an organ console, showing my new design.

FIG. 2 is a right side elevational view, the left side being substantially a mirror image thereof.

The dominant features of my new design are shown in solid lines in the drawing. The conventional manuals fragmentarily shown are continuous within the dot-dash lines as indicated. The grilles fragmentarily shown across the front and side panels are continuous within the boundaries indicated.

I claim:

The ornamental design for an organ console, substantially as shown and described.
